LIGHT SENSITIVE TUBE

Paul Görlich, Dresden, Germany, assignor to
Zeiss Ikon Aktiengesellschaft, Dresden, Germany

Application August 6, 1936, Serial No. 94,589
In Germany August 8, 1935

2 Claims. (Cl. 250—27.5)

The invention relates to improvements in light sensitive tubes and particularly relates to a novel photoelectric cathode for photoelectric tubes.

An object of the invention is to produce a 5 photoelectric cathode which is extremely sensitive in the visible range of the spectrum.

Another object of the invention is the production of a photoelectric layer which may be made 10 sufficiently thin to remain pervious to light. A photoelectric tube equipped with a thin light sensitive layer of this type is particularly suitable for television purposes, since this tube permits the construction of a television apparatus which is adapted for taking television images at day light.

The accompanying drawing illustrates diagrammatically a photoelectric tube provided with a photoelectric cathode in accordance with the present invention.

The envelope 1 of the tube contains an anode 2 and a photoelectric cathode 3. The latter may consist of a layer of antimony or bismuth and a layer of rubidium or caesium alloyed together. In the present instance the photoelectric cathode is mounted on the inner wall of the envelope 1.

The method for producing the light sensitive layer of the invention is as follows: A thin layer of antimony or bismuth is precipitated by evaporation upon a suitable carrier. This layer then preferably is treated with oxygen or its homo-

logues, whereby the oxygen is adsorbed on the layer. Subsequent to this operation caesium or rubidium is precipitated by evaporation upon the antimony or bismuth layer respectively prepared in the described manner. By a heat treatment 5 of the layers, the caesium or rubidium respectively is caused to enter into the antimony or bismuth layer respectively and forms an alloy. The composite coating produced in this manner is extremely sensitive to light and possesses a 10 sensitiveness covering the entire visible range of the spectrum.

If the light sensitive layer is not required to be pervious to light, then the above elements may 15 be precipitated to greater thickness. However, care must be taken always that the alloy will be produced. The employment of rubidium in place of caesium will produce a tube whose highest light sensitiveness is displaced more toward the ultra-violet portion of the spectrum.

What I claim as my invention is:

1. A photoelectric cathode comprising a bismuth layer and a caesium layer alloyed together.

2. A photoelectric cathode consisting of a layer 25 of an element of a group which comprises bismuth and antimony, and a layer of an element of a group which comprises rubidium and caesium, said layers being alloyed together.

PAUL GÖRLICH.
